UNITED STATES PATENT OFFICE.

HECTOR A. PONTECORVO, OF NIAGARA FALLS, NEW YORK.

TAILOR'S MEASURE.

Application filed October 26, 1921. Serial No. 510,568.

To all whom it may concern:

Be it known that I, HECTOR A. PONTECORVO, a subject of the King of Italy, residing at Niagara Falls, in the county of Niagara and State of New York, have invented certain new and useful Improvements in Tailors' Measures, of which the following is a specification.

My invention relates to a tailor's level and measure, and has more particular reference to a device for establishing a level on the garment worn by a person, from which to take measurements.

The primary object of my invention is the provision of a device of this type for establishing a level on a person when taking measurements for clothing and determining any irregularities of the figure, which may be readily accounted for when cutting the pattern for the garment.

Another object of my invention is the provision of a device of this type adapted to be applied to a person to be measured for a garment, and in which a number of parts are adjustable in relation to the conformation of the person being measured to determine the height or elevation of the arm pits, and the width of each shoulder, and to mark a horizontal line across the front and also across the back of the person being measured to determine the width of the front and the width of the back from arm pit to arm pit along said horizontal lines, said lines establishing a base or plane, from a certain point or points of which measurements are taken in different directions of the body according to the adopted method of drawing patterns for garments.

A further object of my invention is the provision of a device of this character, which can be easily folded into a compact space and conveniently carried about, and which is also adjustable to different widths so that it may be as readily applied to persons of slender build, as well as to stouter persons.

A still further object is the provision of a device which is adapted to be applied to a person when taking measurements and supported from the shoulders, and in which spirit levels are included for establishing a level from front to rear, and also crosswise.

With these and other objects to appear hereinafter, the invention consists in the novel features of construction and in the ar-

rangement and combination of parts to be hereinafter described and more particularly pointed out in the subjoined claims.

In the drawings:—

Fig. 1 is a perspective view of the complete device unfolded.

Fig. 2 is a plan view of the same folded.

Fig. 3 is a side elevation of the device, showing the manner in which it is placed upon a person.

Fig. 4 is a plan view of the device unfolded.

Fig. 5 is a transverse section taken on line 5—5, Fig. 3, looking in the direction of the arrow crossing said line.

Fig. 6 is an enlarged transverse section taken on line 6—6, Fig. 4, looking in the direction of the arrow crossing said line.

Fig. 7 is a longitudinal section taken on line 7—7, Fig. 4.

Fig. 8 is an enlarged longitudinal section taken on line 8—8, Fig. 4.

The device has two side members 9, 10 pivotally connected at their rear ends to links 11, 12, which are themselves connected together by shorter links 13. 14, 15 are links similar to the links 11, 12, and these are pivotally connected to the front ends of the side members and are themselves pivotally connected together by shorter links 16. When the device is in use, the links 11, 12 extend rearwardly and inwardly forming a substantially V-shaped rear terminal for the device, while the links 14, 15 extend forwardly and inwardly and also form a V-shaped terminal at the front end of the device. The side members 9, 10 and the links 11, 12, 14 and 15 may be said to constitute a frame, said side members being at all times retained in the same plane, due to the use of the special end connections just described.

Each of the pivots by means of which the side members are connected to the links 11, 12, 14 and 15 extend upwardly through the side members 9, 10, as shown at 17, and to the upwardly extending ends of these pivots, short spiral springs 18 are attached, there being two spiral springs at each side of the frame. Connecting the two spiral springs at each side of the frame are supporting cords 19, which are adapted to be placed over the shoulder of the person. The springs are therefore placed under slight tension and retain the device in any position to which it may be adjusted.

In preferred form, the side members 9, 10 are formed of light weight metallic tubes, the ends of which are closed by means of plugs 20. The links 11, 12, 14 and 15 are 5 also formed of light weight metallic tubes and have their inner ends closed by means of plugs 21, the pivots connecting said links and side members being in the form of screws passed loosely through the plugs of 10 the links and threaded into and through the plugs of the side members, as clearly shown in Fig. 8.

It is to be noted that the side members 9, 10 are curved outwardly at their front ends, 15 their front extremities, however, being in line or substantially in line with the rear straight portions of said side members so that the points of attachment of the front spiral springs are in alinement with the 20 points of attachment of the rear spiral springs, and the supporting cords 19 are therefore parallel. The curving of the side members outwardly, as described, enables the device to be conveniently used on stout 25 women having large bust measurements.

Adjustably secured to each side member are gage arms 22, 23, the front arm of each side member comprising a sleeve 24 which fits onto the tubular side member and is 25 rotatably adjustable thereon. Each sleeve 24 has an upwardly extending socket 25 thereon in which are removably held upwardly tapering gage members 26, preferably formed of wood, the sleeves 24 being 30 held in the desired position lengthwise on the side members and against rotation thereon by set screws 27. Normally, the front gage arms 22 are positioned at the points where the side members commence to curve 35 outwardly, as best shown in Figs. 1 and 4.

Each of the side members is provided with a longitudinal slot 28, and at any desired points along the range of said slots, the rear gage arms 23 are positioned. Each rear gage 40 arm has a saddle-like securing portion 29 which partly surrounds a side member, and an upwardly extending socket 30 into which is an upwardly tapering gage member 31 is 45 removably fitted. The saddle-like securing portion of each rear gage arm is provided with a transverse slot 32, and positioned within each side member is a longitudinally movable filler member 33, into which is threaded a thumb screw 34 which extends 50 through the longitudinal slot 28 of the side member and through the transverse slot 32 of the saddle-like securing portion. Upon 55 loosening the thumb screws 34, the gage arm may be adjusted to the desired position lengthwise on the side member, and also rotatably, if desired.

At the rear end of one of said side members, and if desired, of each of them, a spirit level 36 is placed, said spirit level being cylindrical and fitting into the side member,

which has an opening 37 therein through which the spirit level may be read.

When placing the device on a person for taking measurements to fit garments, the device is unfolded or extended as shown in 70 Figs. 1 and 3, with the gage arms extending upwardly from the side members thereof. When taking measurements, the arms of the person to be measured are placed over the side members so as to bring the latter 75 into the arm pits of the person, with the supporting cords placed over the shoulders and the springs at opposite ends of said cord drawing said side members firmly into the 80 arm pits. The device is then adjusted to position the front gage members 22 against the front of the shoulders, while the rear gage arms 23 are adjusted lengthwise on the side members to bring them directly against 85 the rear of the shoulders, as clearly shown in the drawings. The device so positioned on a person extends rearwardly and also forwardly a distance, as shown in Fig. 3, and when so positioned, the side members 90 are swung upwardly or downwardly at one or the other end until they assume a perfectly horizontal position, which can be 95 readily determined by the spirit level 36, the supporting cords being slid over the shoulders for the purpose of making this adjustment. When properly positioned, the device will be so retained by the spiral 100 springs 17 and the arm gages 22, 23.

Associated with the frame and parts directly connected or attached thereto is a rule or stick 38 having a beveled portion 39 to form what may be termed a knife edge 40. On this rule or stick a spirit level 41 is secured, and when placed in use is supported 105 transversely on the side members 9, 10, as best shown in Figs. 1 and 4. By means of the spirit level 41, the level of the device transversely can be easily determined.

The knife edge of the rule or stick is to 110 be chalked in any suitable manner, tailors' chalk preferably being rubbed along said edge to apply a coat of chalk thereto, and for the purpose of establishing a horizontal line across the chest or front of the person, the chalked edge of the rule or stick is placed thereagainst while the rule rests upon the outwardly curved portions of the side members, the rule or stick being moved lengthwise while in contact with the chest 115 or front to transfer the chalk from the edge of said rule or stick to the garment of the person being marked, at the same time one end after the other of the rule or stick is moved rearwardly while moving the same lengthwise so as to establish an extended line across the front of the person being marked, from arm pit to arm pit.

As often happens to be the case, the region along the spine of some persons is slightly 120 depressed and therefore it is found difficult

- to apply a chalk line to such portion of a person so formed when wearing close fitting garments, and for this reason I have pivotally attached to the under side of the rule 5 or stick a swiveled marker 42, which is formed of sheet metal and has an elongated body portion 43 provided with a depending lip 44 at one end thereof which serves as a handle by means of which the swiveled 10 marker may be conveniently manipulated. Said body portion has its front end tapered, as shown, and it is provided with a longitudinal slot 45 through which is passed a set screw 46 which is threaded into the rule or 15 stick 38, a washer 47 being interposed between the head of said set screw and the under side of said body portion.
- Normally, the elongated body portion is positioned directly underneath the rule or 20 stick and parallel therewith. When, however, it is desired to use the same, the set screw 46 is slightly loosened, the tapered end of the swiveled marker provided with chalk, and said marker positioned at an 25 angle to the rule or stick. The rule or stick is then positioned to rest upon the side members in rear of the body, with the front end thereof in contact with the body. The swiveled marker is then moved forwardly 30 into contact with the body at the depressed portion thereof, and being free to swing on the set screw, the pointed end thereof is moved along the depressed portion of the body so as to properly mark the same while 35 the rule, previously chalked, may itself be moved along the body to establish a mark from the depressed portion of the body outwardly toward opposite side members of the device.
- 40 When marking a garment at the front and rear, the rule rests upon the side members of the device, and at such times the level of the rule or stick may indicate a perfectly horizontal position for the same. If, 45 however, such is not the case, the rule or stick will be elevated at one end until the true horizontal position of the same is indicated by the level thereof, and the exact difference in the height of the low arm pit and the 50 point on the rule or stick directly above the arm pit may be ascertained by any suitable means. When laying out the pattern from which the garment is to be cut, due allowance will be made for the difference so ascertained, and the pattern therefor cut in 55 exact accordance with the irregularity in the body of the person measured; or, if desired, the garment of the person being measured may be marked with the rule or stick 60 while resting with opposite ends against opposite side members of the device, and then be marked a second time after the rule or stick is elevated to a true horizontal position. One method of drawing a pattern 65 may require that both positions of the rule or stick be marked upon the garment; another may require only one position to be marked, due allowance being made for the other; while a third method may require no line to be marked on the garment, as the difference between the two positions of the rule or stick may be ascertained and after squaring the pattern, due allowance be made for the irregularity in the form of a person measured. However, in any event, the irregularity in the shape of the person measured will be ascertained by the two positions of the rule or stick, and the pattern drawn accordingly. I find it of considerable advantage, however, to mark the garment of the person being measured while the rule or stick rests upon opposite side members, and measurements may be taken in various directions from the line mark thus made by using said mark as a base, and when drawing or laying out the pattern, due allowance may be made in the event that the mark thus made is not in a perfectly horizontal plane. Measurements may be taken from the line or base thus shaped by means of a tape measure to determine exact measurements downwardly, upwardly, transversely, and obliquely in any direction, and measurements may also be taken from certain points of the device itself by placing one end of the tape 90 measure at certain points of the device and directing the tape measure from such points to any other point or points of the person being measured, depending on the particular system of measurements employed. 100
- For convenience I fasten to the device at certain points, for example, to one or both sockets 30, one or more lengths of tape, and these I employ for establishing measurements from the socket to the neck or other parts of the body, as indicated in Fig. 5. When employing a single tape for this purpose, the tape may be provided with graduations denoting inches and fractions thereof, or other units of measurements, and when employing more than a single tape, as shown in Fig. 6, these tapes may be of different colors, one being adapted for measurement from the point of attachment to one part of the body, another to a second part, and so on, each tape being employed for a certain measurement, the color denoting the exact measurement or line of measurement under the system of measurements used. These tapes need have no graduation marks thereon, as the exact point to which measurement is taken may be indicated by chalk marks, or otherwise. After securing the desired measurements these tapes may be removed from the device and employed in laying out the pattern of the garment to be cut. For purposes of illustration I have shown three tapes 47, 48, 49, which are fastened in place by a pin 50 inserted through alined openings formed in the socket of the gage arm 115 120 125 130

at diametrically opposite points thereof, the pin being passed through the tapes and through the openings in said socket and the projecting end thereof bent, as shown at 51, 5 to prevent accidental withdrawal of the pin.

With my improved invention in use, the pattern for the garment may be drawn by establishing a base on the pattern paper in conformity with the marks or lines at the 10 front and rear of the person. Any irregularity in the form of the person may be laid out on the pattern in exact accordance with the measurements taken; or, if desired, the marks or lines on the body of the person 15 measured may be used to determine the degree of deviation from a level or horizontal line, and a similar line employed on the pattern as a base from which other measurements may be taken, in which case, even 20 though one arm pit of the person measured is lower than the other, a perfectly fitting garment will be assured.

For convenience in carrying the device, it 25 may be folded as indicated in Fig. 2, in which the links 11, 12 at the rear and the links 14, 15 at the front are swung inwardly between the side members 9, 10, and if desired, the gage members 26, 31 may also be removed from their receiving sockets. 30 When thus folded, the device occupies very little space and may conveniently be carried about.

While the construction shown and described is now considered to be thoroughly 35 practicable, for the purpose intended, the device may be modified in various ways without departing from the invention or sacrificing any of the advantages thereof.

Having thus described my invention, what 40 I claim is:—

1. A device of the kind described, comprising a frame adapted to surround the body of a person at the height of the arm-pits, and means for supporting said frame 45 in position on said person and for drawing said frame into the armpits to permit of taking measurements therefrom.

2. A device of the kind described, comprising a frame having spaced side members adapted to be placed underneath the arm pits of a person, and means for supporting said frame from the shoulders of a person to permit measurements to be taken of the person from different points of said frame and to permit a line to be established transversely on the body from which measurements may be taken.

3. A device of the kind described, comprising two spaced members adapted to be applied to opposite sides of a person, one of said members having a spirit level, and a transverse member laid upon said spaced members and having a spirit level, said transverse member receiving support from 60 said two spaced members.

4. A device of the kind described, comprising a frame having two opposite side members connected together at the rear and front, means for supporting said frame from the shoulders of the person to be measured, 70 and means for determining the exact horizontal position of said frame.

5. A device of the kind described, comprising a pair of opposite side members connected at the front and rear and adapted 75 to be placed at opposite sides of the body of a person to be measured, means for supporting said side members, a gage arm on each of said members, and means for determining the horizontal position of said members. 80

6. A device of the kind described, comprising a pair of side members, links pivotally connected to the ends of said side members and adapted to swing outwardly and rearwardly therefrom, or inwardly and forwardly therefrom, a cord secured to opposite ends of each side member, said cords being adapted to be passed over the shoulders of the person to be measured, and means supported by said side members for marking a line across the body of the person to be measured. 90

7. A device of the kind described, comprising a frame having side members, two pivotally connected links having their outer 95 ends pivotally connected to the rear ends of said side members, two pivotally connected links having their outer ends pivotally connected to the front ends of said side members, a cord attached to each side member at opposite ends thereof, and an arm gage adjustable on each side member. 100

8. A device of the kind described, comprising two side members, links pivotally connected to the rear ends of said side members, shorter links pivotally connecting said links together, links pivotally connected to the front ends of said side members, shorter links pivotally connecting said last-mentioned links together, a pair of relatively 105 adjustable gage arms on each of said side members, and means for supporting said side members from the shoulders of a person to be measured. 110

9. A device of the kind described, comprising side members adjustably connected together at the front and rear, an arm gage on each of said side members, a second arm gage on each of said side members adjustable toward and from said first-mentioned arm gage thereon, and means for supporting said side members in position on the body of the person to be measured. 115

10. A device of the kind described, comprising a pair of side members adjustably 125 connected together at the front and rear, each side member having a longitudinal slot therein, a filler member within each side member, an arm gage on each side member having a transverse slot therein, and a 130

thumb screw extending through said longitudinal and transverse slots and threaded into said filler member for tightening said arm gage on said side member in vertical 5 or any angular position.

11. A device of the kind described, comprising a pair of hollow side members, means adjustably connecting said side members together at their front and rear ends, each side member having a longitudinal slot therein, a filler member longitudinally adjustable within each side member, an arm gage having a saddle-like portion partly surrounding each side member and an upwardly extending socket on said saddle-like portion, a gage member removably fitted into said socket, said saddle-like member having a transverse slot therein, and a thumb screw extending inwardly through 20 said longitudinal and transverse slots and threaded into said filler member.

12. A device of the kind described, comprising a frame, a plurality of differently colored removable tapes secured to said frame, each tape being employed for determining a certain measurement from a point on said frame and being adapted for use when removed in laying out a pattern according to measurements taken.

13. A device of the kind described, comprising a frame having two side members, means adjustably connecting said side members together at their front and rear ends, one of said side members having a spirit 35 level to determine the level of said side members, and a stick associated with said frame and being adapted to rest upon the side members of said frame, said stick having a spirit level thereon to determine the relative positions of said side members.

14. A device of the kind described, comprising a frame having two spaced side members, a spirit level for one of said side members to determine the horizontal position 45 thereof in one direction, a stick associated with said side members and adapted to rest thereon, said stick having a spirit level to determine the true horizontal position thereof in a direction at right angles to said side members.

15. In a device of the kind described, a pair of spaced side members, means adjustably connecting said side members together at their front and rear ends, spiral 55 springs secured to the front and rear ends of said side member, and a supporting cord connecting the spiral springs of each side member, said supporting cords being adapted to support said side members from the shoulders of the person to be measured.

16. A device of the kind described, comprising cylindrical side members, means for supporting said side members on a person at opposite sides of the body thereof, an

arm gage on each side member, and means 65 for adjustably rotating said arm gage on said side member.

17. A device of the kind described, comprising a frame having spaced side members, a stick associated with said frame and adapted to have one edge thereof provided with chalk, said stick being adapted to rest upon opposite side members and be moved with the edge against the person to be measured so as to transfer the chalk there- 75

18. A device of the kind described, comprising a frame having spaced side members, means for supporting said side members from the shoulders of a person to be measured, a stick having a knife edge and being adapted to rest upon said side members, said knife edge being chalked and being adapted to transfer the chalk thereof onto the body of the person to establish a 80 85 line crosswise.

19. A device of the kind described, comprising a frame having two spaced side members adapted to be placed against opposite sides of a person to be measured, a stick resting on said side members, a marker swiveled on said stick and adapted to be positioned transversely of said rule for marking a line on the body of the person 90 95 being measured.

20. A device of the kind described, comprising a frame, means to hang said frame upon a person to be marked and measured and having two spaced parallel members, a stick at right angles to said spaced parallel members and resting thereon, a marker applied to said rule having a longitudinal slot therein, and a pivot extending through said slot to permit said marker to swing thereon, said marker being adapted to have a portion thereof chalked and to transfer the chalk onto the person being measured.

21. A device of the kind described, comprising a pair of hollow side members, plugs closing opposite ends of each side member, a pair of hollow links at the rear of said side members having plugs closing one end of each, pivot screws passed through the plugs of said side members and the plugs of said links and pivotally connecting said links to said side members, means for pivotally connecting said links together, means for supporting said side members from the person to be measured, and means for measuring from said side members to distant points on the person being measured.

22. A device of the kind described, comprising a frame having spaced side members adapted to be placed at opposite sides of the body of a person to be measured, means for yieldingly supporting said side members from the shoulders of said per-

son, and means for measuring from said side member to distant points on the person being measured.

23. A device of the kind described, comprising a frame having spaced side members adapted to be placed at opposite sides of a body of a person to be measured, means

for supporting said side members from the shoulders and drawing the same into the arm pits of said person, and means for measuring from certain points of said side member to distant points on the person. ¹⁰

In testimony whereof I affix my signature.
HECTOR A. PONTECORVO.
